(57) **CLAIM**

I claim the ornamental design for a utility knife, as shown and described.

DESCRIPTION

FIG. 1 is a front and right side perspective view of a utility knife showing the handle of my new design without blades; FIG. 2 is a right side view thereof, the left side view being identical;

FIG. 3 is a front view thereof, the rear view being identical; FIG. 4 is a top view thereof;

FIG. 5 is a bottom view thereof;

FIG. 6 is a bottom and rear perspective view thereof;

FIG. 7 is a front and right side perspective view of FIG. 1 with attached blades;

FIG. 8 is a right side view of FIG. 7;

FIG. 9 is a left side view of FIG. 7;

FIG. 10 is a rear view of FIG. 7;

FIG. 11 is a front view of FIG. 7;

FIG. 12 is a top view of FIG. 7;

FIG. 13 is a bottom view of FIG. 7; and,

FIG. 14 is a bottom and rear perspective view of FIG. 7.
